UNITED STATES PATENT OFFICE.

HARRY H. HUGHES, OF POULTNEY, VERMONT.

ROCK-DRILL ATTACHMENT.

1,159,034.

Specification of Letters Patent.

Patented Nov. 2, 1915.

Application filed May 12, 1914. Serial No. 838,117.

To all whom it may concern:

Be it known that I, HARRY H. HUGHES, a citizen of the United States, residing at Poultney, in the county of Rutland and State of Vermont, have invented certain new and useful Improvements in Rock-Drill Attachments, of which the following is a specification.

This invention has for its primary object the provision of simple and efficient means whereby the bridges or webs left between adjacent holes which are formed by a rock drill may be broken down and the rock split along the desired line of cleavage. Heretofore the generally approved method of splitting the rocks was to drill a line of holes by the use of the rock-drilling machine, and then manually break down the intervening walls or webs by means of a broach held by one workman and blows delivered upon the said broach by hammers in the hands of other workmen to slowly break away said intervening webs or bridges. This operation was laborious and time-consuming and, therefore, expensive. By the use of my improved attachment the intervening webs or bridges may be readily cut away by the use of any rock drill and without requiring the removal of the pawls by which the ordinary drill bit is rotated in the usual operation of the drilling machine. The attachment invented by me is also advantageous in that a rock drill may be frequently employed in locations and in circumstances where the use of a channeling machine is impracticable or impossible. My invention, therefore, contemplates the provision of a tool which may be used in any rock drill and which will be driven into the hole without requiring any change in the manner of operating the drilling machine. The invention also seeks to provide a tool which may be driven into a deeper hole, without change of any of the parts, than has been possible with tools heretofore provided, and finally the invention seeks to improve generally the construction and arrangement of parts whereby the efficiency of a rock drill may be increased.

The invention is illustrated in the accompanying drawings and consists in certain novel features which will be hereinafter first fully described and then more particularly pointed out in the claims following the description.

In the drawings, Figure 1 is an elevation showing my attachment in operative posi-

tion with the cutter lowered in the hole, and illustrating the lowered position of the drill chuck and hammer in full lines and the raised position of the same in dotted lines; 60 Fig. 2 is an enlarged longitudinal section of the hammer and guide forming parts of my invention; Fig. 3 is a perspective view of the same; Fig. 4 is a detail perspective view of the thrust receiving disk. 65

The drilling machine, indicated at 1, may be of any desired construction and is equipped with a chuck 2 adapted to receive the shank of a drill bit in the usual manner, the said shank being retained in the chuck 70 by means of a clamping bolt 3 inserted through the chuck, as will be readily understood. In carrying out my invention I employ a hammer or piston 4 which is provided with a shank 5 adapted to fit within 75 the drill chuck 2 and be secured therein in the same manner as the shank of the ordinary drill bit. This piston or hammer 4 is provided with a socket 5' in its lower end which is adapted to receive the upper end 80 of a guide 6 which may be secured in said socket in any desired manner but is preferably threaded into the same, as illustrated, so that it may be readily removed when necessary. This tubular guide 6 is tapered 85 as shown at 7, so that it may readily enter the hole formed by the drill bit, and in length it exceeds the stroke of the drill so that, when in use, the guide will always be in engagement with the shank of the cutter 90 and will thereby effectually guide the same to the limit of the feed of the drilling machine. A disk 8, which may be of soft steel, or any metal more suitable to the purpose, is fitted in the upper end of the socket 5 over 95 the end of the guide 6 so as to receive the thrust of the drilling machine in the use of the device. The illustrated cutter consists of a stem or bar 9 which is preferably flat sided and has lateral fins or blades 10 at its 100 lower end, the said blades or fins being disposed on radii of the cutter extending parallel with the sides of the bar or stem 9. The upper portion of the bar or stem 9 forms a cylindrical shank 11 which fits within the 105 housing guide 6 loosely enough to permit free movement of the guide upon the shank, but also snugly enough to prevent lateral vibration of the cutter when the device is in use. 110

To prevent rotation of the cutter in the operation of the device so that the work

performed by the cutter will be done upon the bridges or webs between adjacent holes and will not tend to form a spiral groove or grooves in the walls of the holes, I provide 5 a wrench or holder consisting of parallel flat bars 12 which are adapted to extend on opposite sides of the flat bar or stem 9 and are held in spaced relation at one side of the said stem by a bolt 13 extending transversely 10 through them, as will be readily understood. An eye-bolt 14 is mounted upon the bolt 13 and extends beyond the ends of the bars 12 and is equipped with locking nuts 15 to retain a handle 16 upon the eye-bolt. This 15 handle 16 may be held by the operator or may be extended up to the cylinder or body of the drilling machine and fitted in suitable holding and guiding means thereon. It will be readily understood that the engagement 20 of the bars 12 with the flat sides of the stem 9 will prevent rotation of the stem and inasmuch as the blades 10 extend in planes parallel with the flat sides of the stem, the position of the blades will be known even though 25 they may have reached a deep level in the hole. In the operation of the tool, the cutter occasionally strikes a flinty or hard surface which tends to deflect it from its straight course and this action tends to form spiral 30 grooves in the walls of the hole, but the wrench shown and described effectually resists and overcomes the tendency of the cutter to be deflected in the described manner.

It is thought the operation of my improved attachment will be readily understood from the foregoing description taken in connection with the accompanying drawings. The line of holes is formed by the 35 operation of the drilling machine in the usual manner. The drill bit is then removed from the chuck and my improved hammer 4 and guide 6 are substituted therefor. The broach, consisting of the stem 9 with its blades 10 and shank 11, is then placed in 40 position with its shank fitting in the guide 6 and its blades 10 resting upon the webs between adjacent holes extending in the line of the holes or desired line of cleavage. The drilling machine is then operated in the usual manner; the chuck will reciprocate 45 with the piston of the machine and this reciprocating movement will be transmitted directly to the piston 4 and the housing guide 6. The guide 6 will reciprocate upon 50 the shank of the cutter and the blow delivered by the piston of the drilling machine will be transmitted to the upper end of the shank 11 through the piston 4, the force of 55 the blow being expended in the contact of the disk 8 upon the upper end of the shank, as will be readily understood. Inasmuch as the tube 6 in the illustrated arrangement has a circular bore and fits loosely upon the shank 11 having a circular cross-section, it 60 may rotate about the same without impart-

ing rotary movement to the broach and, consequently, the only effect upon the broach will be the driving of the same against the webs or bridges in the rock so that the same will be broken away and the broach caused 70 to descend in the hole previously formed by the rock drill. As above stated, the housing or tubular guide 6 will be longer than the stroke of the drilling machine and, consequently, will be in engagement with the 75 shank 11 at all times, and as the piston is fed forward in the operation of the machine and the broach consequently driven deeper into the hole, the guide will eventually enter the upper end of the hole and the feeding 80 will continue until the lower end of the piston 4 impinges against the upper surface of the rock. In actual practice, the entire length of my broach may be driven into the 85 hole, excepting about one inch of the upper extremity of the shank, whereas in tools which have been heretofore provided, so far as I am aware, over five inches was left exposed above the rock when the machine had 90 been operated to the limit of its movement.

It will here be noted that the guide 6 of the hammer is slidably mounted on but freely separable from the shank 11 of the cutter so that after the ledge is cut, the chuck carrying the guide 6 may be readily detached from the shank of the cutter by elevating the chuck in the usual manner until the lower end of the guide 6 clears the upper end of the shank of the cutter. Such a construction not only permits the cutter to 95 be actuated by the impact of a hammer in cutting the ledge but also permits ready detachment of the guide from the cutter without the necessity of removing screws, bolts and similar fastening devices usually employed for connecting the cutter to the guide. Again, it will be noted that the impact disk 8 is locked in position on the head 100 4 of the hammer by engagement with the upper end of the guide 6, while the enlarged head 4 of the hammer not only affords sufficient weight to drive the cutter when the drill is reciprocated, but by engagement with the rock or surface of the ground serves 105 as a stop to limit the downward movement 110 of the guide within the opening in the rock.

It will be readily noted that my improved attachment may be applied to any rock drilling machine and will not require any 115 change in the construction or manner of operating the same. When the thrust disk 8 has been worn through long continued use, it may be readily removed and a new disk substituted without requiring the provision of a new piston and guide and, consequently, the device may be economically produced and used. When in use, the cutter 120 will be positively supported and the blow for driving the same against or into the rock will be delivered in the axial center 125 130

thereof so that there will be no lateral vibration of the tool. The wrench or holder 12 may be readily adjusted to any desired angle by suitable manipulation of the nuts 5 mounted upon the bolts by which the several parts of the same are connected, and the cutter will move freely forward through the said wrench or holder while at the same time rotation of the cutter will be effectually prevented by the same.

It will be noted that the guide is not attached to the cutter so that there is no lifting action exerted on the cutter which is simply driven ahead and, consequently, 15 there is no liability of either the cutter or the guide breaking and rendering the machine inoperative. Moreover, the cutting end or face of the tool may be formed on the end of the shank and the use of screws 20 or other fastenings are unnecessary. This construction reduces the cost of manufacture and produces a stronger tool and also permits the use of a long shank so that it 25 is not necessary to suspend operations at frequent intervals in order to change the tool as the hole gets deeper. The guide is not packed to form an air tight joint with the shank of the cutter but it is imperforate throughout its length. If the tool be hollow, that is, have a bore extending through 30 its entire length and opening through both its ends, on the up-stroke of the hammer and guide some air will be drawn into the 35 guide and upon the down-stroke this air will be forced through the hollow bore of the tool and out at the lower end of the same where it will blow away the dust and keep the work clean of former cuttings.

Copies of this patent may be obtained for five cents each, by addressing the "Commissioner of Patents, Washington, D. C."

Moreover, if the shank of the tool should tend to upset under the force of the blows 40 delivered thereon by the engine and the hammer, this tendency will be counteracted by the friction between the inside surface of the housing or guide and the outside surface of the tool shank so that the shank 45 will be kept smooth and the machine will operate easily at all times. As the cutter is not lifted until it is withdrawn from the hole after the work is finished, it will always rest squarely on the bed of rock and 50 will not wear away the corners of the cutting point. The machine also can be efficiently operated under a low pressure of steam.

Having thus described my invention, what 55 I claim is:

A hammer attachment adapted to be secured to the chuck of a rock drill, comprising a downwardly tapered head provided with a threaded socket in the lower end 60 thereof, a tubular guiding member threaded into said socket and adapted to loosely telescope with and reciprocate relative to the shank of a cutting member, and an impact 65 disk held in the bottom of the socket of the head by the threaded portion of the tubular guiding member and adapted to impart the hammer blow of the reciprocating head to the shank of the cutting member.

In testimony whereof I affix my signature 70 in presence of two witnesses.
